UNITED STATES PATENT OFFICE.

MATHEW THOMAS LARKIN, OF SPOKANE, WASHINGTON.

RERAILING-FROG HOLDER.

1,216,706.

Specification of Letters Patent. Patented Feb. 20, 1917.

Application filed April 13, 1916. Serial No. 90,987.

To all whom it may concern:

Be it known that I, MATHEW THOMAS LARKIN, a citizen of the United States, residing at Spokane, in the county of Spokane and State of Washington, have invented a new and useful Rerailing-Frog Holder, of which the following is a specification.

This invention relates to improvements in means for holding re-railing frogs which are now usually anchored by spikes, to the ties.

When a locomotive or car has been derailed, great difficulty is experienced in re-railing the locomotive or car for the principal reason that it is difficult to properly anchor the re-railing frogs. The wheels of a de-railed car or locomotive may be sunk deeply in the earth between the ties or the latter may be so rotted and old as to afford no means for holding spikes driven thereinto. When the wheels of a de-railed car are brought to a position of rest upon a worn out tie, or between two ties, it is not only a question of effectively anchoring the frogs for rerailing so that the frogs will be held in such parallel or angular relation to the rail in accordance with requirements, but it is also necessary to hold the re-railing frogs against longitudinal movement resulting from ride-up thrust of the wheels imparted thereto. It will now be clear that the ties not only fail frequently to offer the requisite spike anchorage, but further, the de-railed vehicle seldom stops in such relation to the ties as to permit the re-railing frogs, or rather their spike openings, from properly registering with the ties.

Now the primary object of this invention, broadly speaking, is to provide means for anchoring a re-railing frog to a rail so that the latter will provide a continuous and ever present mounting irrespective of the condition of the ties to anchor the frog thereto either in parallel or angular relation to the rail, the said means not only serving to retain the re-railing frog in such relation to the rail, but also, to prevent longitudinal movement of the frog under wheel ride-up thrust.

More specifically speaking, my invention has to do with means engageable with the

ball of the rail, and with the re-railing frog, for holding the latter in parallel or angular relation to the former, and in the most improved embodiment, said means performs its function by frictionally gripping the ball of the rail. 55

Other features and objects of my invention will be more fully described in connection with the accompanying drawing and will be more particularly pointed out in and by the appended claims. 60

It is a very special and important feature of this invention to provide a frog holder which is adapted for use with the modern type of frog now employed by railroads all over the country so as to avoid the necessity of discarding this valuable stock of frogs and substituting a special type of frog. 65 70

In the drawing:

Figure 1 is a plan view of a left hand rail showing the manner in which the improved device of my invention holds a left hand re-railing frog in relation thereto. 75

Fig. 2 is a sectional view on line 2—2 of Fig. 1.

Fig. 3 is a sectional view of a rail showing the manner in which one of my improved devices is applied thereto. 80

Like characters of reference designate similar parts throughout the different figures of the drawing.

As illustrated, 1 designates the ties and 2 designates the left-hand rail which is mounted on the ties and anchored thereto as usual, by spikes 3. A re-railing left-hand frog 4 is shown disposed in substantially parallel relation to the rail with the ends thereof mounted upon adjacent ties but not in any way spiked or secured thereto. It will be seen that in this position, the spike openings 5, at one end of the frog, overhang the tie so that they would be unavailable in anchoring the frog. These frogs, of the most recent and universal type, are made of pressed steel and they are in the form of elongated hollow bodies, open at the bottom. In order to sustain the great weight to which they are usually subjected, these frog bodies are universally stiffened by transverse ribs or webs 6, 7, 8 and 9, as illustrated for example in the accompanying drawing. 85 90 95 100

The frog has an end-wall 10 and the top

portion is provided with a re-railing guide-way 11 which is diagonally arranged longitudinally along the top of the frog, said top sloping downwardly to an edge 12 adapted to receive the foremost wheel. The side-walls of the frog are indicated at 13 and 14 and the bottom of the frog is provided with studs 15, as shown. While my invention does not reside in the re-railing frog, so much of the same has been described to render the device of my invention clear in its application thereto.

As illustrated, the means for anchoring the frog to the rail comprises one or more devices which may comprise strips of heavy metal, as indicated at 16, one end thereof being shaped to embrace the head or ball of the rail, and the other end thereof being shaped to engage the bottom and a sufficient extent of the interior of one side-wall of the frog so as to extend upwardly between the stiffening webs, as indicated at 17. The terminal end 17 is practically in the form of a hook and the strip 16 is desirably, although not necessarily, of such length that the bight 18, of the hook, is slightly inclined and proportioned to fit in super-posed supported relation on the inner flange 19, of the rail 2. Thus the frog holding device will not only be supported at its frog engaging end, but the frog itself, as regards one side thereof, will be supported directly upon the rail flange through the intermediate bight 18.

Each frog holding device is provided with a rail ball engaging portion, which comprises a section 20 extending across the ball of the rail, a section 21 extending downwardly along the outside face of the ball, and a retaining terminal 22 extending beneath the outer face of the rail ball. The construction is such that the holding device may be applied to a rail in the manner shown in Fig. 3, so that no tools or implements of any kind will be necessary. All of the rail holding devices are identical in formation excepting for the terminal 17 of that device which is disposed nearest the end-wall 10, and designated at 23, this terminal being longer than the terminal 17 of its companion device so that it will not release engagement when the frog end 10 is tilted upwardly as a wheel begins to ride up on the lower end 12. These holding devices preferably fit the ball of the rail in such a manner that they can be adjusted by sliding them along the rail for engagement interiorly of the frog at desired points with respect to the reinforcing webs thereof. Thus in the illustration, one of the devices is engaged with the frog behind web 8, with respect to the direction of wheel thrust, and the other device is engaged behind web 6, with respect to the direction of said thrust.

I will now describe one of the particularly 65 advantageous and broadly novel features whereby these normally loosely applied frog holding devices frictionally wedge themselves in immovable anchorage connection with the ball of the rail responsive to and as a result of any wheel thrust imparted to the end 12.

Such wheel thrust would invariably tend to shift the re-railing frog longitudinally in the direction of the arrow. Now these 75 improved devices are relatively broad so as to present a considerable surface to the ball of the rail. The first result of end thrust would be to cause portions 24 and 25, of each device, to bite against the opposite 80 side faces 26 and 27, of the ball of the rail. In other words, any thrust applied to these devices, end-wise of the rail, would tend to shift the devices out of right angular relation to the rail, and in so doing, the diagonally opposite margins would necessarily tend to bite or wedge against the ball faces. The very loose connection hereinbefore referred to, facilitates this gripping action to prevent shifting movement of the holding 85 devices. Furthermore, in view of the fact that any shifting movement imparted to these devices would be applied to the lower end thereof, below the ball of the rail, it is essential to prevent said devices from tilting 90 on the top of the rail with portions 28 as the fulcrums. Therefore, to avoid such defective action, I provide the retaining terminals 22, equal in width to the widths of the strip of which the holding device is made, 100 this retaining device engaging the rail ball at one of its under faces to prevent tilting movement of the holding devices. The greatest end thrust is applied when the first wheel begins to ride up on the frog, but 105 there will be a certain amount of end thrust as a result of ride-up engagement of the next following wheel. However, with the tremendous weight of one wheel on the frog, the following end thrust will not usually be 110 as great as the initial thrust.

While in Fig. 1, I have shown the re-railing frog in parallel relation with the rail, and being held by two devices, it will be understood that one of said devices will 115 be sufficient when it is desired to swing the lower end 12 away from the rail to register with a de-railed truck wheel located a considerable distance from the rail, as shown in dotted line in Fig. 1. Thus I do not wish 120 to be confined to the use of two holding devices for each frog. It will also be understood that while I have only shown my invention applied to a left-hand frog, its application to a right-hand frog will be identical and therefore need not be illustrated.

I also assert that my invention is novel as an article of manufacture, one phase of

novelty being a single device having portions for engagement with a rail and a re-railing frog for holding the latter in re-railing relation to said rail.

5 While I have herein shown one specific form of my invention, I do not wish to be limited thereto except for such limitations as the claims may import.

I claim:

10 1. In combination, a railway rail, a re-railing frog, and a plurality of unitary means connected with said rail and frog in a manner capable of holding the latter in re-railing relation to said rail independently 15 of any engagement of said frog with the road bed or with said rail, substantially as described.

2. In combination, a railway rail, a re-railing frog, having angularly disposed portions, and a plurality of unitary means grip- 20 pingly engaging said rail and abuttingly 25 engaging said angularly disposed portions of said frog in a manner capable of holding the latter in substantially parallel relation to the rail independently of any engagement 30 of said frog with the road bed or with the rail, substantially as described.

3. In combination, a railway rail, a re-railing frog, and a unitary integral device 35 grippingly engaging said rail and abuttingly 40 engaging said frog for holding the latter in angular relation with the rail without the necessity of any engagement of said frog with the road bed, substantially as 45 described.

4. In combination, a railway rail, a re-railing frog, and independent unitary devices grippingly engaging said rail and abuttingly 40 engaging said frog in a manner capable of positively holding the latter in substantially parallel relation with the rail independently 45 of any engagement of said frog with the road bed or with said rail, substantially as described.

45 5. In combination, a railway rail, a re-railing frog having sets of angularly disposed portions, and unitary devices grip- 50 pingly engaging said rail and each of said devices engaging a set of said angularly disposed portions of said frog for positively holding the latter in substantially parallel relation with said rail without the necessity 55 of any engagement of said frog with the road bed or with said rail, substantially as described.

6. In combination, a railway rail, a re-railing frog, and unitary means engaging the top, side and bottom portions of the ball of the rail and also engaging said frog 60 to hold the latter in re-railing relation to the rail without the necessity of any engagement of the frog with the road bed, substantially as described.

7. In combination, a railway rail, a hollow

re-railing frog provided with internal stiffening webs, and means engaging said rail and the webs of said frog to hold the latter in re-railing relation to said rail, substantially as described. 65

8. In combination, a railway rail, a re-railing frog, and unitary means engaging said rail at a single area of engagement along the length of said rail and connected with said frog for holding the latter in re-railing relation to said rail without the necessity of any engagement of said frog with the road bed or with portions of said rail other than said single area, substantially as described. 70 75

9. In combination, a railway rail, a re-railing frog, and means engaging the ball of said rail and extending pendently downward and loosely engaging said frog below said rail ball for holding said frog in re-railing relation to said rail, substantially as described. 80 85

10. In combination, a railway rail, a re-railing frog, and means engaging the ball of said rail and extending pendently downwardly and engaging said frog at a point below the ball of said rail for holding said frog in spaced re-railing relation to said rail, said means gripping the ball of said rail to prevent horizontal or vertical tilting movement of said means, substantially as 90 95 described.

11. In combination, a railway rail, a re-railing frog, and a frog holding device extending up along one side face of the ball of said rail and transversely across the tread of said ball and downwardly along the other side face of said ball and having a retaining portion extending beneath one portion of the ball of the rail, and said device having a portion for holding said frog in re-railing relation to the rail without the necessity of any engagement of the frog with the road bed, substantially as 100 105 described.

12. In combination, a railway rail, a re-railing frog, and a frog holding device connected with said frog and in supported engagement with the ball of said rail and also with one flange of said rail, substantially as described. 110

13. In combination, a railway rail, a re-railing frog, and a frog holding device comprising a bar having one terminal shaped to engage over the ball of the rail and another terminal shaped to engage and be 115 capable of holding the frog in re-railing relation to the rail independently of any engagement of the frog with the ties or road bed. 120

14. As an article of manufacture, a single piece re-railing frog holder having an engaging portion shaped to grip the ball of the rail and a frog holding portion. 125

15. As an article of manufacture, a single piece re-railing frog holder having one portion shaped to grip the ball of a rail and another portion shaped for connection with a re-railing frog, substantially as described.

16. As an article of manufacture, a re-railing frog holder having an end portion

for engaging the ball of the rail and a frog holding engaging end, said holder having an intermediate rail flange engaging portion, substantially as described. 10

In testimony that I claim the foregoing as my own, I hereby affix my signature.

MATHEW THOMAS LARKIN.
